UNITED STATES PATENT OFFICE.

SAMUEL P. CHAPMAN, OF DUBLIN, GEORGIA.

AMUSEMENT DEVICE.

1,319,643.

Specification of Letters Patent. Patented Oct. 21, 1919.

Application filed January 12, 1918. Serial No. 211,609.

To all whom it may concern:

Be it known that I, SAMUEL P. CHAPMAN, a citizen of the United States, residing at Dublin, in the county of Laurens and State 5 of Georgia, have invented new and useful Improvements in Amusement Devices, of which the following is a specification.

This invention relates to an amusement device, and the object is to provide in connection with a supporting framework a rotating member carrying a plurality of aeroplanes, and means for causing the aeroplanes to travel at varying elevations during their movement in a circular path.

10 15 A further object is to provide a rotating member and a supporting device or track which may be placed in any desired angular position for controlling the position of the aeroplanes, and causing them to travel in 20 an undulatory path.

A still further object is to provide means for automatically maintaining the correct position of the aeroplanes during the operation of the apparatus.

25 In the drawings—

Figure 1 is a view of the device in side elevation.

Fig. 2 is also a side elevation, one side being broken away, and certain of the elements 30 being in different position from the position of Fig. 1.

Fig. 3 is a detail view showing the means for attaching the aeroplanes.

Fig. 4 is a fragmentary view of a portion 35 of the mounting means for the rotating element.

The framework includes a base comprising a plurality of members 10 and 12, while upwardly inclined members 14 are secured 40 to the ends of said members first named and approach each other at the upper portion of the framework where a bearing member 15 is provided for the accommodation of the vertically mounted shaft 16. This shaft 16 45 carries a pulley 17 having connection with any suitable source of power.

The cross arm 18 is rotated by the shaft 16 and carries at the ends thereof a plurality of aeroplanes which are caused to travel in a 50 circular path when the apparatus is in operation. The brackets 20 provide bearings for rollers 21 supporting cross arm 18 on ring member 22 the latter being pivotally supported on opposite sides by pins 22'. Member 22 is capable of angular movement and 55 throws cross arm 18 into a corresponding

angular position. The pivotal point of the cross arm is shown at 24 and the position of this arm is governed by means of a manually operated device including an arm 25 connected at 26 with a bell crank lever 27, the opposite end of which lever is connected with a rod 28 which controls the position of ring member 22, thereby tilting the cross arm or returning the latter to a horizontal 60 position. Bracing means for the cross arm include stay wires or cables 27' secured at points 28'.

The aeroplanes are each maintained in correct position by means of cables 30 and 31 70 connected with the opposite ends of levers 32 and 33, one of these levers being carried by the cross arm and the other by one of the aeroplanes. These levers 32 and 33 are connected by a rod or rods 34 with a frame 75 35 on the upper portion of the main shaft.

The aeroplane includes a body portion 40 and a plurality of wings 41 and 42, rollers or small wheels being provided at 43 for contact with the ground when the end of the 80 arm 18 is depressed for loading or unloading purposes. The spring 45 mounted between two arms 46 47 is designed to prevent the aeroplane from swinging outwardly from its direct path of travel when the machine 85 is in motion. Each aeroplane is connected with the cross arm at 48 by means of a suitable connecting device 49 and is capable of movement with reference to the cross arm so that the aeroplanes may drop in the direction shown in Fig. 2 when the machine is 90 not in operation.

A swinging seat for the passengers is shown at 38. The upper part 38' of the seat frame appears in dotted lines in Fig. 3, 95 the latter being a top plan view. During the unloading operation the angle of the ring member 22 is changed permitting one of the aeroplanes to approach the ground, and the plane gradually assumes an approximately vertical position, the rear end finally resting on the ground. When the passengers have alighted the rotation of the device causes the plane to rise and at the same time owing to the inclination of the ring member 22, the other plane will descend for unloading. The seats are, of course, maintained in their normal or vertical position in view of the pivotal mounting thereof.

100 What is claimed is:

1. In a device of the class described, a framework, a vertically mounted shaft

110

105

therein, a cross arm mounted on said shaft and rotated thereby, means for changing the angular position of the cross arm during rotation, passenger carrying devices supported by the cross arm, said means for changing the angular position of the cross arm including an annular track member the opposite sides of which are pivotally mounted, and means for tilting the annular track member to various positions.

2. In a device of the class described, a framework, a vertical shaft mounted therein, a cross arm carried by said shaft and rotated thereby, means for mounting the cross arm and permitting its position to be shifted in a vertical plane, an annular track member, means carried by the cross arm and bearing on said ring member, and means for

tilting the track member to various positions.

3. In a device of the class described, a framework, a shaft mounted for rotation therein, a cross arm carried by the shaft and rotated thereby, an annular and pivotally mounted track member, means for changing the angular relation thereof for shifting the position of the cross arm during rotation, aeroplanes pivotally connected at their forward portions with the ends of the cross arm, and resilient devices for limiting lateral swinging movement of the aeroplanes during the rotation of the shaft and cross arm.
